Assistant Examiner — Adrienne Corra

(57) **CLAIM**

The ornamental design for a shoe outsole as shown and described.

DESCRIPTION

FIG. 1 is a front, right and top perspective view of a shoe outsole showing my new design;

FIG. 2 is a front, left and top perspective view;

FIG. 3 is a rear, right and bottom perspective view thereof;

FIG. 4 is a front elevational view thereof;

FIG. 5 is a rear elevational view thereof;

FIG. 6 is a left view thereof;

FIG. 7 is a right view thereof;

FIG. 8 is a top plan view thereof;

FIG. 9 is a bottom plan view thereof;

FIG. 10 is an enlarged view of a portion labeled as 10 on FIG. 2;

FIG. 11 is an enlarged view of a portion labeled as 11 on FIG. 4;

FIG. 12 is an enlarged view of a portion labeled as 12 on FIG. 5; and,

FIG. 13 is an enlarged view of a portion labeled as 13 on FIG. 9.

The long dash-short dash broken lines depict enlargement boundaries that form no part of the claimed design.

1 Claim, 13 Drawing Sheets
